UNITED STATES PATENT OFFICE.

ADOLPH G. HUPFEL, OF NEW YORK, N. Y., ASSIGNOR TO MICHAEL FLECK, OF NEW YORK, N. Y.

STABLE-FLOORING.

No. 821,417.

Specification of Letters Patent.

Patented May 22, 1906.

Application filed January 29, 1906. Serial No. 298,362.

To all whom it may concern:

Be it known that I, ADOLPH G. HUPFEL, a citizen of the United States, and a resident of New York, county of New York, and State of New York, have invented a new and useful Improvement in Stable-Flooring, of which the following is a specification, the principle of the invention being herein explained and the best mode in which I have contemplated applying that principle, so as to distinguish it from other inventions.

My invention relates to flooring for stables, and particularly for the stalls in stables.

The superior advantages of stone or cement as forming a dry and enduring foundation for stables or stalls have long been recognized; but it is objectionable to have the animals, especially horses, stand on the hard surface which these materials present. Accordingly numerous attempts have been heretofore made to combine with such stone or cement foundation a plank floor properly disposed within the stall for the animal to stand upon.

The object of my present invention is to provide a floor of this character that will be simple and inexpensive in its construction as well as easily removable for the purpose of cleansing the stall and for its own repair.

To this end my invention consists of means hereinafter fully described, and particularly set forth in the claims.

The annexed drawings and the following description set forth in detail certain means embodying the invention, such disclosed means constituting but one of various forms in which the principle of the invention may be used.

In said annexed drawings, Figure 1 represents a plan view of a portion of a stable including two stalls embodying my improvement; and Fig. 2 represents a vertical longitudinal cross-section of one of said stalls, taken upon a plane passing through the line 22, Fig. 1.

In Fig. 1 two stall areas A A are shown, separated from each other by a suitable partition B. The foundation E of such stalls is made of cement or similar material, so as to be impervious to moisture. To facilitate the drainage of the stalls, a gutter or drain C extends along their rear, and the surface of the stalls, as also of the adjacent part of the alley-

way in the rear of such stalls, is downwardly inclined toward such drain.

In each stall area A, I depress that portion of the foundation which it is desired to floor with plank, so as to form a shallow basin or recess A'. Such basin or recess A' is preferably of rectangular outline, as shown in aforesaid Fig. 1. It may of course cover the entire stall area, if desired, although here shown as being somewhat smaller than such area and centrally disposed therein. The rear end of recess A' opens directly into gutter C, and the inclination of its bottom being the same as that of the stall-foundation it is readily apparent that it will be perfectly drained.

To form the plank flooring before referred to, I use a series of slats a of approximately the length of recesses A'. These are longitudinally disposed in each recess, so as to leave a narrow opening between adjacent slats, thus affording a free passage for the urine or other liquids through to the cement bottom, over which it flows to the gutter C, and thus escapes. The depth of the recess A' and the thickness of slats a should be the same, or nearly so, in order that the surface of the stall may be smooth and level. Inasmuch as such slats were they merely loosely laid in the recess A' would readily become displaced by the stamping of the animal in the stall, it is necessary to provide means for securing them in their places. For this purpose I provide in the bottom of the recess and near each end a series of vertically-projecting pins a', equal in number to the number of slats a, designed to occupy such recess and preferably disposed in a transverse line, so as to lie in each case the same distance from the end of the slats. These pins, which would of course ordinarily be made of iron, are independent of each other and are embedded in the cement foundation of the stall at the time of the laying of the same. Their lower ends should be provided with heads a² or similar means, whereby they are firmly anchored in such foundation, and their disposition vertically should be such as to bring their upper ends below the level of the stall-floor proper. In other words, they should extend above the bottom of the recess a distance equal to a little less than half the depth of such recess.

Each slat a of the plank flooring is provided with apertures a³, disposed so as to register

when the slat is properly placed in the recess with two of these pins, one at each end. Each aperture a^3 should extend entirely through the slat, and the two apertures in any slat 5 should be equidistant from its ends to correspond with the arrangement of the pins a' .

Since it is desirable to have the entire area planked upon which the horse stands, while only the rear portion of such area requires 10 to be made removable for the purpose of cleansing the stall, I insert permanently in the forward end of the recess A one or more transverse planks a^4 . In this way I lengthen the standing floor for the horse and at the same 15 time shorten the movable planks, so that they may be cut from standard-length planks. Moreover, since these transverse planks do not wear out so rapidly as the removable slats there is a considerable saving as to the 20 cost of repairs.

The construction of my improved stable-flooring having thus been fully described, the manner of its use will require but little explanation. It should be pointed out, however, 25 that by the disposition of apertures a^3 in the slats, as well as by having them extend entirely through the slats, the latter may not only be turned end for end, but also turned bottom side over, and the effects of wear and 30 warping thus counteracted. The ease with which they may be taken up and again placed in position not only adapts them for this purpose, but also renders cleansing of the stall a very simple matter, there being no mechanism 35 whatever involved in the structure. This last feature is particularly noteworthy, since the building of a flooring as above described involves no special parts nor material not readily obtainable in any locality. At the 40 same time there is nothing liable to breakage or apt to get out of order.

Having thus described my invention in detail, that which I particularly point out and distinctly claim is—

45 1. In a stall, the combination with a recessed foundation, of a series of pins projecting above the bottom of such recess, and flooring-slats fitted to such recess and provided with apertures adapted to register with 50 said pins.

2. In a stall, the combination with a re-

cessed foundation, of a series of pins embedded in said foundation and projecting above the bottom of such recess, and flooring-slats fitted to said recess and provided with apertures adapted to register with said pins. 55

3. In a stall, the combination with a recessed foundation, of a series of pins embedded in said foundation and projecting above the bottom of such recess, and flooring-slats 60 fitted to said recess and provided with apertures adapted to register with said pins; such apertures extending entirely through said slats, whereby the latter are adapted to be turned over. 65

4. In a stall, the combination with a recessed foundation, of a series of independent pins embedded in said foundation and projecting above the bottom of such recess, and flooring-slats fitted to said recess and provided with apertures adapted to register with 70 said pins; such apertures extending entirely through said slats, whereby the latter are adapted to be turned over. 75

5. In a stall, the combination with a foundation having a recess therein, a series of pins embedded in said foundation near each end of said recess and projecting above the bottom of the latter, and flooring-slats fitted to said recess and provided with apertures 80 adapted to register with said pins; the disposition of said pins and apertures being such as to permit the turning of said slats end for end, and said apertures extending entirely through said slats whereby the latter are 85 adapted to be turned over.

6. In a stall, the combination with a recessed foundation, of a series of independent pins embedded in said foundation and projecting above the bottom of such recess, 90 flooring-slats longitudinally fitted to said recess and provided with apertures adapted to register with said pins, and one or more transverse slats permanently secured in the forward end of said recess. 95

Signed by me this 14th day of January, 1906.

ADOLPH G. HUPFEL.
